UNITED STATES PATENT OFFICE.

JOSEPH MATUSHAK, OF WALLINGTON, NEW JERSEY, ASSIGNOR OF ONE-HALF TO
FRANK J. STEYSKAL, OF PASSAIC, NEW JERSEY.

DOLL-CARRIAGE.

1,058,881.

Specification of Letters Patent.

Patented Apr. 15, 1913.

Application filed June 14, 1912. Serial No. 703,737.

To all whom it may concern:

Be it known that I, JOSEPH MATUSHAK, citizen of the United States, residing at Wallington, in the county of Bergen and 5 State of New Jersey, have invented certain new and useful Improvements in Doll-Carriages, of which the following is a specification.

My invention relates to new and useful 10 improvements in toys and more particularly to doll carriages, and the object of my invention is to provide a doll carriage having a revolving platform and cage adapted to be actuated by the rotation of the wheels during 15 the movement of the carriage.

A further object of my invention is to provide a doll carriage including a wheeled body member having cradles mounted for 20 rocking movement and adapted to be actuated by the movement of the carriage.

A still further object of my invention is to provide a direct drive between the rear axle of the carriage and the revolving platform and to provide means operable by the 25 revolving of the platform for rocking the cradles.

With these and other objects in view, my 30 invention will be more fully described, illustrated in the accompanying drawings and then specifically pointed out in the claims which are attached to and form a part of this application.

In the drawings: Figure 1 is a perspective view of my improved doll carriage; Fig. 35 2 is a central longitudinal section of the same showing the drive mechanism between the rear axle and the revolving platform and also the mechanism by means of which the motion of the platform is transmitted to 40 rock the cradles; Fig. 3 is a bottom plan view of the carriage, the casings over the driving mechanism being removed to better show the parts; Fig. 4 is a detail perspective of one of the crank shafts operable by 45 the rotation of the platform and transmitting power to the cradle.

Corresponding and like parts are referred to in the following description and indicated in all the views of the drawings by the same 50 reference characters.

The preferred embodiment of my inven-

tion primarily includes a wheeled body member 10, a revolving platform and cage designated as a whole by the numeral 11 and cradles 12 and 13 mounted for swinging movement between the sides of the body member.

More particularly the body member includes a base consisting of a rectangular shaped frame preferably formed of wood, 60 having side members 14 and 15 and end members 16 and 17, the side members being preferably reinforced centrally by braces 18 secured to the inner faces of the side members and by transversely extending, spaced 65 braces 19. Secured upon this frame is the floor of the carriage 20 and extending vertically upward from the frame are the side members 21 and end members 22 of the carriage, said floor, side and end members being 70 also preferably formed of wood.

Journaled in suitable bearings 23 secured in alined relation upon the lower faces of the side members 14 and 15 of the carriage frame and adjacent the forward end thereof 75 is a forward axle 24 which is held against longitudinal movement through its bearings by collars 25 and set screws 26 and upon the ends of which are mounted the supporting wheels 27 which may be of any desired type 80 and which are preferably provided with a rubber tread 28.

Similarly journaled in bearings 29 carried by the rear portions of the side members of the frame is a rear axle 30 maintained 85 against longitudinal movement by collars 31 and set screws 32 and keyed or otherwise secured against rotation upon the free ends of this axle, are the rear bearing wheels 33 also having rubber treads. 90

The floor of the carriage is provided centrally with a vertical bore through which is passed one end of a sleeve 34 which is provided intermediate its length with a laterally directed flange 35 which seats in an annular recess formed in the central portion of a circular revolving platform 36. Screws or bolts 37 are passed through the flange and engage in the platform to lock the same against movement upon the sleeve. The 95 platform is maintained in spaced relation above the floor of the carriage by means of 100

friction rollers 38 which are keyed upon the inner ends of crank shafts 39 journaled in suitable bearings 40 carried by the floor of the carriage.

- 5 Extending through the sleeve 34, is a vertical and preferably tubular shaft 41, the lower end of which carries a beveled gear 42 which meshes with a beveled gear 43 carried by the forward end of a longitudinally extending drive shaft 44 which is journaled in bearings formed in the braces 19 and the rear end of which carries a beveled gear 45 meshing with a beveled gear 46 keyed upon the rear axle 30. The shaft 41 is locked against rotation in the sleeve by means of a set screw 47. It will thus be seen that upon the turning of the rear wheels of the carriage the motion will be transmitted through the axle, drive shaft and shaft 41 to rotate the platform 36. Extending vertically upward from the platform 36 and at right angles to each other, are intersecting arch members 48. As shown, the free end of the shaft 41 passes through 25 the juncture of these arches and through the base 49, of a cylindrical cage 50.

Fanciful representations of animals, such as horses, are mounted upon the revolving platform 36 and are supported in place by pins 51 which pass through the upright portions of the arches and the inner ends of which are engaged in sockets formed in the bodies of the figures. If desired the staff 52 of a flag may be inserted in the upper end 35 of the tubular shaft 41. In order to clearly and successively expose the figures of the animals to view, I have cut away the central portions of the side members of the body as shown at 53, and inserted arched frames 54 40 through which the figures are clearly visible.

The cradles 12 and 13 are identical in construction and the description of one will therefore suffice for both. Each cradle member comprises a base, end walls 55, and downwardly converging side walls 56. Each of the end walls is provided with an outwardly directed trunnion 57 which seats in a suitable bearing formed upon the inner face of the side members of the carriage. As 45 shown these cradles are so proportioned as to exactly fit between the side members of the carriage when extended transversely thereof and are positioned one at the front and one at the rear of the carriage.

55 Extending rearwardly from the bottom of the cradle 12 and forwardly from the bottom of the cradle 13 are arms 58 the free ends of which are swingingly connected to one end of links 59, the other ends of which 60 are connected to the crank arms 60 of the crank shafts 39. As will be readily seen when the platform 36 is revolved through the turning of the rear axle of the carriage it will act upon the supporting friction

wheels 38 to rotate the crank shafts which 65 in turn will act through the links and lever arms to rock the cradles. The friction wheels 38 are preferably provided with a tread of rubber or other suitable material 70 to increase the friction between them and the platform. Dolls may be placed both in the cage 50 and in the cradles 12 and 13.

Extending upwardly and rearwardly from the side portions of the rear end of the carriage body, are standards 63 having rearwardly curved terminals 64 connected by a cross brace 65 which forms a handle for moving the carriage along the ground. The gears 45 and 46 and the gears 42 and 43 are preferably inclosed by suitable casings 66 80 and 67 respectively.

From the foregoing description, taken in connection with the drawings, the operation of the toy will be apparent, and no description of the same is necessary.

Having thus described the invention, what is claimed as new is:

1. A doll carriage including a wheeled body member, a revoluble platform carried by the body member, cradles mounted for 90 rocking movement in the body member, means operable by the movement of the carriage for revolving the platform, and means operable by the movement of the platform for rocking the cradles.

2. A doll carriage including a wheeled body member, a vertically extending shaft rotatably mounted through the floor of said body member, means operable by the movement of the carriage for rotating said shaft, 100 a platform carried by the shaft, oppositely disposed longitudinally extending crank shafts, friction wheels carried by the adjacent ends of said crank shafts and supporting the platform, transversely extending 105 cradles mounted for rocking movement in the end portions of the body member, and means coacting between said cradles and the crank arms of the crank shafts to transmit the motion of the platform to the cradles.

3. A doll carriage including a wheeled body member, a revoluble platform carried by the body member, cradles mounted for 115 rocking movement in the body member, a live axle, a train of gears operating between said axle and the revoluble platform, and means operable by the revolving of the platform for rocking the cradle.

4. A doll carriage including a wheeled body member, a revoluble platform carried 120 by the body member, cradles mounted for rocking movement in the body member, means operable by the movement of the carriage for revolving the platform, bearing wheels supporting the platform, shafts upon 125 which said wheels are keyed, and means operable by the rotation of said shafts for rocking the cradles.

5. A doll carriage including a wheeled body member, shafts journaled in the body member, bearing wheels carried by the shafts, a revoluble platform supported upon said bearing wheels, cradles mounted for rocking movement in the body member, means operable by the movement of the carriage for revolving the platform, and means

operable by the revolving of the shafts for rocking the cradles. 10

In testimony whereof I affix my signature in presence of two witnesses.
